UNITED STATES PATENT OFFICE

2,591,266

BOTTLE CRATE AND LINER THEREFOR

Joe Kuchel, Arlington, Va.

Application December 5, 1947, Serial No. 789,889

4 Claims. (Cl. 217—19)

1

This invention relates to a paper liner for beer, milk or soft drink cases or the like.

An object of the invention is to provide a paper liner for cases of the above mentioned type, that will separate the bottles in the case, yet will, with little effort, quickly reload the bottles from the liner and the case.

Another object of the invention is to provide a unique structure of this character that is simple in structure, easily and cheaply constructed and efficient and durable in its performance of the use for which it is designed.

With the above and other objects and advantages in view, the invention consists of the novel details of construction, arrangement and combination of parts more fully hereinafter described, claimed and illustrated in the accompanying drawings in which:

Figure 1 is a perspective view of an embodiment of the invention showing the manner in which it is lifted from a beer case or the like.

Figure 2 is a plan view of the blank from which the device is formed;

Figure 3 is a detailed perspective view of the scored portion on which each bottle will rest;

Figure 4 is a plan view of a partially filled beer case or the like, partly broken away and partly in section, to show the bottom of the case;

Figure 5 is a sectional view on the line 5—5 of Figure 4;

Figure 6 is a sectional view on the line 6—6 of Figure 4, and

Figure 7 is a fragmentary perspective view, partly in section, of the liner and case.

Referring more in detail to the drawings, the reference numeral 10 designates a beer case or the like in which the liner 11 embodying the invention is adapted to be positioned.

Cases of the type usually used for containing beer bottles or the like comprise a wooden frame composed of side walls 12 and end walls 13. The end walls 13 each are provided with hand grip openings 14, by means of which the case is conveniently carried.

In this instance, the case is provided with a metal bottom 15, having relatively spaced circular openings 16 therein, which are of a size slightly larger than the bottles that are to be placed in the case.

The liner 11 comprising the invention is formed from the blank shown in Figure 2. This blank, when properly shaped by bending, will comprise ends 17 and a bottom 18. The ends 17 are provided with hand grip openings 19 which are to be used in lifting the liner, as shown in Figure 1.

2

The bottom 18, on its lower surface, is provided with circular recesses 20, and these recesses are of a size to conform to the size of the openings 16 in the bottom 15.

When the liner 11 is placed in the case, the recesses 20 and openings 16 will align themselves, one with the other, so that the liner will accomplish the objects of the invention previously set forth.

The upper surface of the bottom 18 is cut along the several lines 21, to form V-shaped sections 22, and these sections provide bottle locating recesses for receiving the bottles 23, as shown in Figures 5 and 6.

The liner or liners 11 are placed in the case 10 according to the size of the case, as shown in the various figures. A separator or partition 24 is placed between each liner, and the conventional web 25 will be placed in each liner to divide the case into individual compartments. The web 25, as is the usual custom, extends from the bottom of the case to a point slightly above the half-way mark in the case, to prevent the bottles from striking each other and damaging them by breakage or the like.

The liner 11 is made of a material that will permit the bottles to pass through the sections and recesses in the bottom thereof, and then permit the sections to spring back into place after the bottle has passed through.

In use, the liners are placed in the case, the separator and webs are placed in position, and the bottles placed in the individual compartments formed by the webs.

The sections 22 are strong enough to support each bottle as the case or liner is carried, but a slight downward pressure on the bottle will force the bottle through the sections.

In placing the case in a cooler, the whole case may be placed therein or a liner may be removed from the case and placed in the cooler. The bottles are pressed downward for a slight distance as shown in Figure 1 by raising one end of the liner with one hand and pressing the adjacent bottles downward with the other, and then raising the other end of the liner with one hand and pressing the remaining bottles downward, then by shaking the case of the liner, the bottles will drop from the liner or case into the cooler.

The liner provides a quick and convenient means for placing the bottles in a cooler, or otherwise carrying the bottles to a place at which the bottles are to be deposited.

The liner can be made of a heavy cardboard

or any other inexpensive material that will accomplish the purposes of the invention, as set forth.

It is believed that from the foregoing description, the construction and manner of use of the invention will be apparent to those skilled in the art, and it is to be understood that changes in the minor details of construction, arrangement and combination of parts may be resorted to, provided they fall within the spirit of the invention and the scope of the appended claims.

Having thus described the invention, what is claimed as new and desired to be secured by Letters Patent is:

1. In a bottle case of the type described, having a bottom structure provided with a plurality of relatively spaced circular openings, a liner in said case, V-shaped sections in said liner overlying said openings, slits outlining said sections so that a bottle resting on said sections may be pushed therethrough outwardly of the bottom through the openings therein.

2. In a bottle case of the type described having a bottom structure provided with a plurality of relatively spaced circular openings, the improvement comprising a liner in said case and said liner comprising a rectangular shaped blank having a bottom portion and oppositely disposed end portions, circular recesses in the lower surface of the bottom portion, and slits in the upper surface of the bottom portion forming V-shaped sections which overlie the recesses in the lower surface thereof, and said recesses overlying the openings in the bottom structure of the case so that a bottle resting on said V-shaped sections may be pushed therethrough outwardly of the bottom through the openings therein.

3. The combination of a bottle case having a bottom structure provided with a plurality of relatively spaced circular openings and a liner

comprising a flat U-shaped sheet of material with hand openings in the upper parts of the ends, and a filler for positioning bottles on the liner, said liner having a plurality of recesses with radially disposed slits therein registering with the positions of bottles on the liner and providing means whereby bottles may be pressed through the liner, and the openings in the bottom of the case outwardly thereof.

4. The combination of a bottle case having a bottom structure provided with a plurality of relatively spaced circular openings and a liner comprising a rectangular-shaped sheet of material formed with an intermediate section and with the ends extending upwardly and having hand openings in the upwardly extending ends of the ends, the intermediate portion of the liner having spaced bottle receiving openings with inwardly extending flaps in the openings adapted to support bottles on the liner, and wherein the bottles pass through the openings with slight pressure, to move outwardly of the openings in the bottom of the case.

JOE KUCHEL.
